UNITED STATES PATENT OFFICE.

GARRETT L. GRIER AND FRANK L. GRIER, OF MILFORD, DELAWARE.

SANITARY HOLDER FOR SHADE-GUIDES.

1,078,431.

Specification of Letters Patent. Patented Nov. 11, 1913.

Application filed January 21, 1913. Serial No. 743,332.

To all whom it may concern:

Be it known that we, GARRETT L. GRIER and FRANK L. GRIER, citizens of the United States, and residents of Milford, in the 5 county of Sussex and State of Delaware, have made certain new and useful Improvements in Sanitary Holders for Shade-Guides, of which the following is a specification.

10 Our invention relates to improvements in means for holding shade guides, and it consists in the combinations, constructions and arrangements herein described and claimed.

15 An object of our invention is to provide a device for holding samples of cement that are to be used as shade guides so that the latter may be in a moistened state and instantly ready for use in determining the 20 shade of cement to be used in filling a tooth:

A further object of our invention is to provide a holder for the shade guides which will keep the latter free from dust or germs 25 that might come in contact with them if kept in a drawer or upon a table.

30 A further object of our invention is to provide a holder which will fit readily into the palm of the hand but which will permit the ready selection of the different samples.

35 Other objects and advantages will appear in the following specification, and the novel features of the device will be particularly pointed out in the appended claims.

40 Our invention is illustrated in the accompanying drawings forming part of this application in which—

Figure 1 is a vertical section through the device, Fig. 2 is an enlarged perspective view of the suspending ring and a portion of the strips, and Fig. 3 is a sectional view of a modified form of the device.

45 The process of matching cement samples with teeth in which the apparatus which forms the subject of the present invention is used is set forth in a copending application, Serial No. 743,333, filed Jan. 21, 1913.

50 In carrying out our invention we provide a bottle or other similar receptacle 1 of the shape shown in Fig. 1. This bottle is provided with a stopper 2 of the same material, and having a handle or knob 3. The underside of the stopper is provided with a bore 4 arranged to receive the stem 5 of a ring 6.

55 In the drawings we have shown the stem

5 as consisting of the adjacent ends of the ring 6 although it may be a single integral stem without departing from the spirit of the invention. This stem is held in the bore 4 by means of cement 7.

60 Suspended from the ring 6 are a series of strips 8 which are slideable on the ring and also have a pivotal movement with respect thereto. These strips are preferably 65 of a thin resilient waterproof material, such as celluloid, or the like, and bear at their lower end the shade guides 9. The latter are really pieces of cement of various tints or shades, each formed in the shape of a tooth. As will be seen from the drawing, 70 the lower ends of the strips 8 with the cement samples are submerged beneath water.

75 In filling a tooth with cement it is often difficult to attain the right color. The cement is put up in the form of powder and is mixed with phosphoric acid into a paste, and one is very liable to get the cement filling either darker or lighter than the tooth itself. With our process, however, this liability of error is reduced to a minimum. 80 The cement shades or samples are already made up and are kept submerged under water in the bottle 1. When it is necessary to determine the shade of cement to be used the stopper 3 is removed and held in the 85 palm of the hand, while the strips 8 are separated with the fingers, and the cement samples or shade guides in their moist condition may be placed along side of the tooth to be treated. Unless the cement is moistened it will not be of the shade that it has when placed in the cavity of a tooth, for when the cement is dry it will appear generally of a lighter shade. The shade guides are numbered to correspond with 90 the powders from which they are made, so that the proper shades can be readily ascertained. As soon as the selection is made, the stopper is returned to its place, the shade guides again being submerged in the 95 water where they are kept free from contamination and ready for instant use.

100 It will be seen that the placing of the shade guides under water serve a double purpose. It keeps them in a moistened condition so that they do not have to be moistened when they are removed from the bottle, besides keeping them in a perfectly sanitary state. The stopper 2 serves, as stated, as a handle for manipulating the 110

shade guides with the fingers and also as a means of suspension for the shade guides when the latter are submerged in water.

In Fig. 3 we have shown a modified form 5 of the device in which the bottle 1 is provided with a cap 10. The neck of the bottle is provided on the interior with inwardly projecting lugs 1^a. The ring 6 which supports the strips 8 bearing the 10 shade guides 9 is adapted to rest on the lugs 1^a and a handle 11 is provided for lifting the shade guides out of the bottle when they may be used as already described.

We claim:

- 15 1. In a sanitary holder for shade guides, a receptacle for containing water, a series of shade guides, and means for suspending said shade guides in the water in said receptacle, said suspending means constituting 20 a common handle for said shade guides.
2. In a sanitary shade guide holder, a receptacle for containing water, a series of shade guides, means for pivotally securing said shade guides together, means for suspending 25 said pivotal means to permit the immersion of the shade guides in the water in the receptacle, and a closure for said receptacle adapted to surmount said shade guides when the latter are immersed in 30 water.
3. In a sanitary shade guide holder, a covered receptacle for containing water, a series of shade guides pivotally secured together, means for suspending said shade 35 guides in the water, in said covered receptacle, and a common handle for the series

of shade guides, said common handle also serving as a closure for the receptacle.

4. A sanitary shade guide holder comprising a receptacle for containing water, a plurality of strips pivotally secured together and bearing cement samples at their lower ends, and a stopper for said receptacle, the pivotal support of said strips being secured to said stopper. 45

5. A sanitary shade guide holder comprising a receptacle for containing water, a plurality of strips bearing cement samples at their lower ends, a ring for suspending the said strips, a stem secured to said ring, 50 a stopper for the mouth of said receptacle provided with a bore on its under side adapted to receive said stem, and means for retaining said stem within the bore.

6. A sanitary shade guide holder comprising a receptacle for containing water, a plurality of strips bearing cement samples at their lower ends, a ring for suspending the said strips, a stem secured to said ring, 55 a stopper for the mouth of said receptacle provided with a bore on its under side adapted to receive said stem, and means for retaining said stem within the bore, the cement samples being normally underneath the water when the stopper is in the mouth 60 of the receptacle.
